Primary Examiner — Natasha Vujcic(74) *Attorney, Agent, or Firm* — Boudwin Intellectual Property(57) **CLAIM**

The ornamental design for an electronic license plate, shown and described.

DESCRIPTION

FIG. 1 shows a perspective view of an electronic license plate;

FIG. 2 shows a front view of the electronic license plate;

FIG. 3 shows a rear view of the electronic license plate;

FIG. 4 shows a right side view of the electronic license plate;

FIG. 5 shows a left side view of the electronic license plate; and,

FIG. 6 shows a top plan view of the electronic license plate; and,

FIG. 7 shows a bottom plan view of the electronic license plate.

The shade lines in the Figures show contour and not surface ornamentation.

The broken lines shown in the Figures show portions of the electronic license plate which form no part of the claimed design.

1 Claim, 3 Drawing Sheets(56)
